INVENTOR:
ALFRED GILBERT
BY: *Frank Oldham*
ATTORNEY.

UNITED STATES PATENT OFFICE.

ALFRED GILBERT, OF BIRMINGHAM, ENGLAND.

MANUFACTURE OF BOOK-FILES FOR CARDS AND THE LIKE.

1,399,550.

Specification of Letters Patent.

Patented Dec. 6, 1921.

Application filed December 24, 1918. Serial No. 263,186.

To all whom it may concern:

Be it known that I, ALFRED GILBERT, a subject of the King of Great Britain, residing at 27 Hickman road, Sparkbrook, Birmingham, in the county of Warwick, England, have invented a new and useful Improvement in the Manufacture of Book-Files for Cards and the like; and I do hereby declare the following to be a full, clear, and exact description of the same.

My invention comprises improvements in the manufacture of book files for cards and the like, more particularly of files of the kind wherein the leaves of the book are provided with cords or the like forming loops for carrying a number of cards or the like in such a manner that the whole of the cards are simultaneously displayed.

In one prior form of file the cords pass across the corners of the card to be filed, these cords being threaded through holes preferably eyeleted. The threading of these cords has hitherto been effected by hand and the object of the present invention is to enable this to be done in a cheaper and more expeditious manner.

According to this invention the cord is applied by means of a sewing machine which makes a long stitch extending as across the corner of the card and beneath which the corner of the card may be inserted.

The sewing machine employed is of that kind which is adapted to stop or to be stopped after each descent of the needle, such machines being commonly used for embroidery purposes and being known as "fanning" machines.

In the accompanying drawings:

Figure 1 illustrates a leaf for a file manufactured according to this invention.

Fig. 2 is a sectional view through part of same.

Fig. 3 illustrates a leaf showing a modified arrangement of threads.

In carrying this invention into practice as illustrated upon the accompanying drawings, the paper or cardboard 1 from which the file is to be produced is placed beneath the sewing machine and the needle then descends at a point adjacent one of the corners of the card (4) position, making the first stitch. The machine then stops under the control of a clutch and the leaf 1 of the

file is moved to a position adjacent the next side of the card position and so as to cross the corner thereof, after which the machine is restarted, making another stitch at this point and thus producing a long loop on each face of the paper. The operation is repeated so as to provide loops around one or more of the cards.

Figs. 1-3 show two forms of the finished article in one of which, illustrated by Figs. 1 and 2, the cards 4 are secured beneath the cords 24 which are tied at the starting point and at the finish, this being attained by making a double stitch at these points, these two stitches being indicated by 26 and 27. The loose ends of the cords may also be braided and secured by a seal 28 or the like. Fig. 2 shows an enlarged section illustrating one form of stitch which may be employed and known as a "lock stitch". In Fig. 3 an arrangement of cords 24 in substantially octagonal form is shown whereby the cards 4 may be secured with their longest sides vertical as shown or horizontal as shown by the dotted lines.

In the case of loose leaf files the stitch may start adjacent the binding edge of the sheet so that when the sheets are clamped together the threads will be firmly held by the pressure between the sheets.

In the prior form to which I have referred, in the event of the cord breaking at any one point the whole length of cord would become loose, but according to this invention, by making a double or treble stitch at each point, each short length or loop of cord is firmly locked so that breakage of one loop will not affect any of the other loops.

What I claim is:-

1. A leaf for book files comprising card-holding strands of cord adapted to receive beneath them and hold the corners of cards to the leaf, said strands being mutually secured to the leaf by lock-stitching.

2. A leaf for a book file for cards comprising a sheet upon both surfaces of which are formed a series of long stitches adapted to hold the corners of cards, the cords forming the stitches upon the upper and lower surfaces of the sheet being looped or united together at the ends of the stitches.

3. A leaf for a book file for cards comprising a sheet upon both surfaces of which

are formed a series of long stitches adapted to hold the corners of cards, all the long stitches upon one side of the sheet being formed from one length of cord and all the long stitches upon the other side of the sheet being formed from another length of cord, the two lengths of cord being united to

gether by one of them passing through the sheet and engaging with the other at the ends of each long stitch.

10

In testimony whereof, I have signed my name to this specification.

ALFRED GILBERT.
